CLAIM

The ornamental design for a trailer hitch marking system, as shown and described.

DESCRIPTION

FIG. 1 is a front-side perspective view of a trailer hitch chain marking component of a trailer hitch marking system showing my new design;

FIG. 2 is a front elevational view of the trailer hitch chain marking component of the trailer hitch marking system depicted in FIG. 1;

FIG. 3 is a rear elevational view of the trailer hitch chain marking component of the trailer hitch marking system depicted in FIG. 1;

FIG. 4 is a top plan view of the trailer hitch chain marking component of the trailer hitch marking system depicted in FIG. 1;

FIG. 5 is a bottom plan view of the trailer hitch chain marking component of the trailer hitch marking system depicted in FIG. 1;

FIG. 6 is a left side elevational view of the trailer hitch chain marking component of the trailer hitch marking system depicted in FIG. 1;

FIG. 7 is a right side elevational view of the trailer hitch chain marking component of the trailer hitch marking system depicted in FIG. 1; and,

FIG. 8 is a rear-side perspective view of the trailer hitch chain marking component of the trailer hitch marking system depicted in FIG. 1.

The broken line portions of the drawing figures are included to show unclaimed subject matter only and form no part of the claimed design. In particular, the raised textured pattern portions and the trailer hitch ball sizes on the trailer hitch chain marking component form no part of the claimed invention.

1 Claim, 5 Drawing Sheets
